UNITED STATES PATENT OFFICE.

ANITA G. HYAMS AND FRANCIS A. HYAMS, OF SAN RAFAEL, CALIFORNIA.

SACK-LINING MACHINE.

1,381,419.

Specification of Letters Patent. Patented June 14, 1921.

Application filed April 20, 1920. Serial No. 375,416.

To all whom it may concern:

Be it known that we, ANITA G. HYAMS and FRANCIS A. HYAMS, citizens of the United States, residing at San Rafael, in the 5 county of Marin, State of California, have invented a new and useful Sack-Lining Machine, of which the following is a specification in such full and clear terms as will enable those skilled in the art to construct 10 and use the same.

This invention relates to a machine for lining sacks and its object is to place one sack within another.

It will be understood by those skilled in 15 the art that in the handling of sugar and some other commodities that jute bags are used, which are provided with an inner liner of a closer fabric, as for example, in the case of sugar, a jute bag is lined with a fine cotton sack.

In the present invention the jute bags are placed upon a support and the cotton bag is placed upon another support whereupon suitable arms push the cotton bag into the jute 25 bag and project the corners of the cotton bag into the corners of the jute bag and then pull the two bags off their supports and push them toward a pair of rollers, which rollers pull the bags off the apparatus for placing 30 the cotton bag within the jute bag and remove them to a suitable place of storage.

Other objects of the invention will appear as the description proceeds.

An embodiment of the invention is shown 35 in the accompanying drawings in which the same reference numeral is applied to the same portion throughout, but I am aware that there may be modifications thereof.

Figure 1 is a side elevation of the complete apparatus.

Fig. 2 is a front elevation of the complete apparatus with the table for supporting the liner removed for purposes of illustration.

Fig. 3 is a perspective view of the two 45 bags in position for the liner to be inserted within the jute bag.

The apparatus comprises a pair of vertically extending bars 1 and 2 which are connected at their upper ends to suitable members 3 and 4 to form the ceiling joists of the plant in which the machine is installed and braces 5 and 6 are used to connect the members 1 and 2 with said joists to give them additional stiffness.

At the lower ends, the bars 1 and 2 are

connected to a pair of braces 8 and 9 on one side and to braces 10 and 11 on the other side. Connecting the members 1 and 2 are cross bars 13 and 14 and two guides 15 and 16 extend from the lower cross bar 13 to the ceiling joists 17 and 18 and additional cross bars 19 to 24 inclusive connecting with the bars 1 and 2, serve to hold the guides 15 and 16 in their proper position.

The cross arm 13 supports two large balls 25 and 26 and a stiff spring 27 carries a similar large ball 28 which stands in front of the center of the machine. Vertically movable in the slot between the guides 15 and 16 is a slide 29, having two arms 30 and 31 pivotally mounted thereon, which arms have knobs 32 and 33 at their lower ends. The upper ends of these arms have rollers 34 and 35 therein which travel in inclined guides 36 and 37. The object being 75 to bring the two knobs 32 and 33 to a position between the two knobs 25 and 26 when the liner sack is to be placed in position.

The slide 29 is operated by means of a 80 large wheel 40 on a shaft 41, journaled in bearings 42 and 43, which hang down from a suitable frame 44 attached to the ceiling of the room in which the machine is installed.

A pulley 45 serves to supply power to the shaft 41. The wheel 40 is pivotally connected to a pitman 46 which has its upper end connected to the slide 29 so that as the wheel 40 rotates, the slide 29 and the arms 30 and 31 are raised and lowered.

Attached to the braces 8 and 10 respectively are two stiff spiral springs 46 and 47, which support large knobs 48 and 49. Platforms 50 and 51 are provided for the operators and a table 52 is provided for the support of the liner sack, while it is being pushed into the outside sack.

The table 52 is supported upon suitable posts 53 and 54 and the platforms 50 and 51 are supported upon suitable posts 55 to 58 inclusive, which posts also serve to support bars for the shafts 59 to 62 inclusive. The shafts 59 and 62 carry rollers 63 and 64 over which an endless conveyer 65 passes. The shafts 60 and 61 carry rollers 65 and 66, the latter of which is in contact with the upper surface of the endless conveyer 65'. The object of positioning the rollers as described is to provide means whereby the 110

conveyer belt 65' will drive the roller 66 and thereby drive the roller 65 to pull the sacks off the sack holding apparatus and deliver them to the conveyer to be carried 5 to a place of storage.

The operation of the machine is as follows: The operators stand on the platforms 50 and 51 and as the arms 30 and 31 rise and fall continuously the operator on the 10 platform 50 will place a jute sack on the knobs 48 and 49 the springs being stiff enough to hold the sack in place with some tension at the same time the operator on the platform 51 will place the liner sack on 15 the two knobs 25 and 26 and will spring the knob 28 into the mouth of the sack so that it will assume the position shown in Fig. 3.

After the sack has been placed as shown 20 in Fig. 3, the arms 30 and 31 will descend and finally push the corners of the liner into the corner of the jute sack. Ordinarily the jute sack will hang down to the position indicated in dotted lines in Fig. 2, so that 25 when the arms 30 and 31 reach the bottom of the sack they will continue to descend and pull the sack off the knobs 48 and 49 and pull the liner sack off its supporting knobs and push the two sacks between the 30 two rollers 65 and 66. Said rollers will then pull the sack off the arms and the endless conveyer 65' will discharge the two sacks to the right Fig. 1 to a suitable place of storage.

In order to prevent the arms 30 and 31 35 from pulling the liner sack off the edge of the outer sack and pulling the latter off its supporting knobs, a rod 70 is connected with the two vertical members 1 and 2 and extends across the front of the machine just 40 below the plane of the supporting knobs for the liner and above the plane of the knobs 48 and 49 for supporting the outer sack.

The result of this is that the liner is pulled 45 off the rod of the support until the liner is pushed far enough into the outer sack to insure its proper disposition therein.

What we claim is as follows, but various 50 modifications may be made in the construction shown in the drawings and above particularly described form, within the purview of our invention:

1. A machine for lining sacks comprising a suitable frame, a pair of sack supports carried thereby, supports for a second sack at a 55 distance from the first supports and a pair of reciprocating arms adapted to push the second sack into the first sack.

2. A sack lining machine comprising a

supporting frame, a pair of spring sack supports carried thereby, other supports for a second sack at a distance from the first supports, a pair of arms adapted to push the second sack into the first sack and means to spread said arms to push the corners of the second sack into the corners of the first sack. 60 65

3. A sack lining machine comprising a supporting frame, a pair of spring sack supports carried thereby, other supports for a second sack at a distance from the first supports, a pair of reciprocating arms adapted 70 to push the second sack into the first sack, means to spread said arms to push the corners of the second sack into the corners of the first sack and means to pull the two sacks off the supports. 75

4. A sack lining machine comprising a supporting frame work, a pair of spring supports carried thereby, other supports for a second sack, means to push the second sack into the first sack, a pair of rollers to pull 80 the two sacks off their supports and an endless conveyer for delivering the sacks to a suitable place of storage when passed through the pair of rollers.

5. A sack lining machine comprising a 85 supporting frame work, a pair of spring sack supports carried thereby, other supports for a second sack above the first supports, a pair of reciprocating arms adapted to push the second sack into the first sack, 90 means to spread said arms to push the corners of the second sack into the corners of the first sack, a pair of rollers to pull the two sacks off the arms and supports therefor and an endless conveyer to discharge the sacks 95 to a suitable place of storage when pulled off the sack supports.

6. A sack lining machine comprising a supporting frame work, a pair of spring sack supports carried thereby, fixed supports for a second sack, a spring support in the plane 100 of the second supports, a pair of reciprocating arms adapted to push the second sack into the first sack, means to spread the arms 105 to push the corners of the second sack into the corners of the first sack, a pair of rollers between which the sacks are pushed on the end of the stroke of the reciprocating arms and an endless belt in contact with one of said rollers to discharge the sacks to a suitable place of storage. 110

In testimony whereof we have hereunto set our hands this 8th day of April, A. D. 1920.

ANITA G. HYAMS.
FRANCIS A. HYAMS.
